A. P. STORRS.
CHIMNEY FOR INCANDESCENT BURNERS.
APPLICATION FILED FEB. 10, 1914.

UNITED STATES PATENT OFFICE.

AARON P. STORRS, OF OWEIGO, NEW YORK, ASSIGNOR TO STORRS MICA COMPANY, OF OWEIGO, NEW YORK, A CORPORATION OF NEW YORK.

CHIMNEY FOR INCANDESCENT BURNERS.

1,129,135.

Specification of Letters Patent.

Patented Feb. 23, 1915.

Application filed February 10, 1914. Serial No. 817,729.

To all whom it may concern:

Be it known that I, AARON P. STORRS, a citizen of the United States, residing in the village of Owego, county of Tioga, and 5 State of New York, have invented a certain new and useful Chimney for Incandescent Burners, of which the following is a specification.

The object I have in view is the production of an improved means for attaching a gas mantle to a mica chimney.

This invention is of the same type as that forming the subject-matter of my Patent 1,066,060, granted July 1, 1913.

15 By my invention, I seek to simplify the attachment, and to make the parts of the device capable of being assembled with great ease.

A further object is to avoid the necessity 20 of a separate fastening means.

These and further objects will appear from the following specification and accompanying drawings, considered together or separately.

25 In the drawings, Figure 1 is a plan view of a chimney embodying my invention, in place upon a mantle ring, the latter being shown in connection with a burner tip which is drawn in section. Fig. 2 is a section on

30 the line 2—2 of Fig. 1. Fig. 3 is a plan view of the upper part of the chimney, showing the position of the parts, before the attachment of the chimney to the mantle ring. Fig. 4 is a sectional view on the line

35 4—4 of Fig. 3. Fig. 5 is a cross-section, of the metal band, at the top of the chimney, before the flaps are bent to final position. Fig. 6 is a perspective view of one of the tubular extensions used in connection with

40 the mantle ring illustrated in Fig. 1. Fig. 7 is a plan view of a modification; and Fig. 8 is a section on the line 8—8 of Fig. 7.

In all of the views, like parts are designated by the same reference characters.

45 Referring to the drawing, 1 represents a chimney which is formed of transparent material, preferably mica. I prefer to make the chimney of several sheets of mica to reduce cost. The number of sheets that is used is immaterial. The bottom of the chimney is bound with a metal protecting casing, and may have a mica or wire gauze bottom sheet, as shown, for the purpose of inclosing

50 the burner and collecting the deposits

from the mantle and burner. The usual 55 ventilating openings are shown near the bottom of the chimney, together with an opening in the center of the bottom sheet for the introduction of the igniting flame from the pilot light.

60 The details shown and just described, are for purposes of illustration, of a particular embodiment of the invention.

I make no claim herein to the particular 65 form of chimney just described.

The upper part of the chimney is provided with a metal band 2, which carries means for attaching the mantle to the chimney. The details of this band will be described later. The burner tip 3 shown, is 70 of the usual form and carries the usual mantle ring 4, and inverted mantle 5. The common form of mantle ring illustrated is provided with a plurality of integral elbows 6 and fingers 7 which are adapted to engage 75 with and be supported by lugs (not shown) on the burner tip 3. The elbows 6, according to my invention, are utilized to engage with and support the chimney 1. The chimney with the mantle and mantle ring are preferably 80 combined, and in such condition they may be sold together and thereby constitute an article of manufacture.

The combination of the chimney, mantle and ring may be easily attached to the 85 burner tip by passing the ring around the burner tip and giving the chimney a partial turn, so as to lock the fingers 7 with the usual lugs on the burner tip (not shown). This may be accomplished by an unskilled 90 person without need of touching the mantle.

In order to readily turn the mantle ring so as to lock on the burner tip, it is necessary that the mantle ring be properly secured to the chimney so that the ring may 95 be rotated on the burner tip and that the ring will be properly secured to the chimney. It is also desirable that the mantle

ring may be readily removed from the chimney, and another ring with a fresh mantle 100 substituted. This is all easily accomplished by the following mechanism. According to the preferred form of my invention, I provide tubular extensions 9 (see Fig. 6) for the elbows 6, 6. Each of these is preferably 105 made of sheet metal of such a size that it snugly fits around the elbow 6. These extensions are of such a length that when in

place on the elbows 6, 6, 6, they will fit within notches 10, 10, 10, formed in the metal band 2. The elbows 6 and extensions 9 form arms which, when they are in engagement with the notches, support the chimney in place on the mantle ring. Should it be desirable to use a chimney of extremely small diameter, the extensions may be removed and the elbows 6 brought into direct engagement with the notches. In some situations it may be desirable to make the elbows 6 long enough to directly engage chimneys of standard size or even larger. Each notch is provided with a side flap 11, adapted to engage with the side of the tubular extension which is in the notch. It is also provided with an end flap 12, adapted to lie beyond the end of the extension, and hold the latter against horizontal displacement.

Fig. 5 shows the best way of making the notches and flaps. Two cuts are made in the proper place on the metal band, said cuts being angularly arranged, as shown. The place between the cuts constitutes the end flap 12. The apex of this flap is squared, as shown, so that there will not be a sharp point which would otherwise injure the finger of the person applying the mantle ring in place. One side of the notch is bent outward, as shown in Figs. 3 and 4, and this constitutes the side flap 11. Either side of the notch may be chosen to be bent out, if desired. Both sides may be bent out if desired, but I find that only one is necessary to produce an opening wide enough to permit introduction of the end of the elbow or of the extension. The end flaps are bent out at the base, and then up, a short distance above the base. This is well shown in Fig. 4. The perimeter of the end flaps is slightly greater than the perimeter of the tubular extensions 9, when the latter are in place on the arm 6. The notches 10 are, of course, located upon the band 2 in proper position, so that when the extensions are placed upon the elbows 6, 6, 6, the said extensions may be simultaneously seated within all of the notches in the band. When seated, the ends of the extensions will come into engagement with the end flaps. The side flaps 11 are then bent to the original position. When this is done, they thereby inclose the upper parts of the notches 10, and keep the extensions 9 in place in the notches. The material forming the band 2 is sufficiently ductile to permit the side flaps to be bent outward and inward a number of times, so that the mantle ring may be removed and a new one substituted as many times as is necessary, whenever the mantles require renewing.

The tubular extensions 9, 9 are desirable where a mantle ring with arms of the usual length are employed. Figs. 7 and 8 illustrate a mantle ring with elbows of sufficient

length to engage with the chimney, without the necessity of the employment of the extensions.

According to my invention, as hereinbefore described, the elbows on the mantle ring, or the elbows alone, provided they be sufficiently long, constitutes arms which engage with the chimney.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:—

1. A chimney with notches on its upper edge, in combination with a mantle ring, means carried by the ring, which engage with the notches, whereby the chimney will be supported.

2. A chimney and a mantle ring, said chimney having notches in its upper edge, means carried by the ring for engaging with the notches and means for closing the notches, whereby the chimney will be supported.

3. A chimney having a metal band at the top, notches in the band, side flaps at the sides of the notches, in combination with a mantle ring with projecting arms, said arms lying within the notches and being engaged by the side flaps.

4. A chimney with a metal band at its upper edge, notches in the band, side flaps on the sides of the notches, end flaps, in combination with a mantle ring, with projecting arms, said arms lying within the notches and being engaged by the end and side flaps.

5. A chimney with a metal band at its upper edge, notches in the band, and end flaps opposite each notch, in combination with a mantle ring, having projecting arms, said arms lying within the notches, and in line with the end flaps.

6. A chimney with notches in its upper edge and flexible members adjacent to the notches, in combination with a mantle ring, arms carried by the ring, said arms resting in the notches and said flexible members engaging with arms to retain them in position.

7. A chimney with notches on its upper edge, in combination with a mantle ring, adjustable means carried by the ring for engaging with the notches, and means for chimney will be supported.

8. A chimney and a mantle ring, said chimney having notches in its upper edge, adjustable means carried by the ring for engaging with the notches, and means for closing the notches.

9. A chimney having a metal band at the

top, notches in the band, flaps at the sides of the notches, in combination with a mantle ring, adjustable, radially projecting arms carried by the ring, said arms lying within the notches and engaged by the flaps.

10. A chimney with a metal band at its upper edge, notches in the band, flaps on the sides of the notches, and end flaps, in combination with a mantle ring, said mantle ring having adjustable arms lying within the notches and engaging the end flaps.

15. A chimney with a metal band at its upper edge, notches in the band, flaps on the sides of the notches and end flaps, in combination with a mantle ring, said ring having adjustable arms lying within the notches and engaging the side and end flaps.

20. A chimney with a metal band at its upper edge and flaps on said band, in combination with a mantle ring, and adjustable arms carried by the ring and engaging with said flaps.

25. A chimney with a metal band at its upper edge, notches in the band, and end flaps opposite each notch, in combination with a mantle ring and adjustable arms carried by the ring, said arms lying within the notches and in line with the flaps.

14. A chimney with a metal band at its

upper edge and flaps on said band, said flaps 30 being bent to form tables, the ends of the flaps being turned up to form end members, in combination with a mantle ring, arms carried by the ring, said arms resting on the table and engaging the end members.

35. 15. A chimney with notches in its upper edge, in combination with a mantle ring with arms, tubular extensions on the arms, engaging with the notches, whereby the chimney will be supported.

40. 16. A chimney with notches in its upper edge, in combination with a mantle ring, elbows carried by the ring and adjustable members on the elbows, said members engaging the notches to support the chimney. 45

17. A chimney with notches in its upper edge and flexible members adjacent to the notches, in combination with a mantle ring, and adjustable tubular members on the rings, said members resting in the notches 50 and said flexible members being bent over to retain the tubular members in position.

This specification signed and witnessed this ninth day of February, 1914.

AARON P. STORRS.
